LARYNGOSCOPE

Ernst Trier Mörch, Kansas City, Kans.

Application October 18, 1951, Serial No. 251,883

4 Claims. (Cl. 128—11)

1

The present invention relates in general to medical and surgical instruments, and it deals more particularly with laryngoscopes.

It is the object of the invention, broadly speaking, to provide an improved form of laryngoscope which is relatively simple and economical to construct and to use; which is versatile and readily adapted for use with patients of all ages and sizes; which is rugged and durable; and in which the critical components may easily be sterilized, using standard equipment and techniques.

A feature of the invention resides in providing a handle capable of receiving a variety of interchangeable blades for use in laryngoscopy, and a particularly important feature lies in the arrangement I provide for detachably mounting the blades on the handle.

Another object is to provide a laryngoscope having novel means for illuminating the interior of the throat and larynx to be examined by the laryngoscopist. According to my invention, the blades carry no lamp bulbs or other electrical components, a factor which contributes to their economy and at the same time obviates the difficulties which heretofore have attended the sterilization of such blades. Another important feature resides in the manner in which I have assembled all of the electrical components, including a light source, on the handle of my unit in a compact and sturdy assembly which may readily be detached from the blades for the purpose of sterilizing the latter or for substituting one blade for another. Still another feature lies in my arrangement for concentrating and focusing upon the parts being examined, light from a light source positioned on the handle of my device and hence spaced at a considerable distance from said parts.

Another object is to provide a laryngoscope having a compact self-contained source of electrical power for energizing the light source, whereby the unit is portable and easily manipulated by the laryngoscopist. In the latter connection, a further feature resides in the provision of a circuit controlling switch of novel construction.

Other objects of the invention, together with additional features of novelty whereby such objects are achieved, will appear in the course of the following description.

In the accompanying drawings which form a part of the specification and are to be read in conjunction therewith, and in which like reference numerals are employed to indicate like parts of the various views:

Fig. 1 is a side elevational view of my laryngoscope, indicating its mode of use in connection with a diagrammatic showing of a patient,

2

Fig. 2 is a fragmentary perspective view of the laryngoscope, illustrating a preferred form of blade and also showing the upper end of the handle upon which the blade is adapted to be mounted.

Fig. 3 is an enlarged transverse cross section taken along the line 3—3 of Fig. 1 in the direction of the arrows,

Fig. 4 is an enlarged transverse cross section taken along the line 4—4 of Fig. 1 in the direction of the arrows, and

Fig. 5 is an exploded view of the major switch components of my unit.

Referring more particularly to the drawings, 15 the handle 10 of my laryngoscope comprises a tubular shell or housing which is adapted to receive a pair of dry cells 12 of the flashlight battery type, these being disposed end to end in a manner well known to those familiar with the use of such cells.

One end of the housing is closed by a headpiece 14 which is secured in place by screws 16. The headpiece will be described in more detail presently but it may be noted at this point that it contains a socket 18 for receiving a small incandescent lamp 20. One terminal of the lamp is in direct contact with the headpiece and thus is connected through the headpiece to the metallic shell 10; the other lamp terminal is connected by an insulated conductor (not shown) extending through the headpiece to the central post of the upper dry cell.

The opposite end of the tubular housing 10 is internally threaded to receive a screw cap 22, the latter having an outwardly extending annular shoulder 24, which abuts against the end of the housing to limit the distance the cap can be screwed into the housing. Within the cap there is a circular well 26 which receives a generally disc-shaped insulator 28; as best seen in Fig. 5, the insulator has a pair of integral laterally spaced legs 28a adapted to seat against the bottom of the well and hold the main body of the insulator spaced above the bottom as shown in Fig. 4. A screw 30 extending through a central hole in the end of the cap 22 and into a threaded hole 28b in the insulator holds the latter in place in the well.

The upper face of the insulator 28 contains a circular recess 28c in which is seated the large end of a generally conical compression spring 32. The small end of the spring presses upwardly on the base of the lower dry cell 12 to make electrical contact therewith and also to maintain the cells in contact with one another as is well known in the art. The lower end of the spring extends

through the insulator and has its tip 34 bent over, both to anchor the spring and also to serve as an electrical contact.

Encircling the cap 22 between the end of shell 10 and the shoulder 36 on the cap is a knurled ring 38 which is free to turn on the cap when the latter is screwed tightly into the shell as aforementioned. The ring contains a small circular aperture 40 and behind this aperture the cap has a circumferentially elongated slot 42. A pin 44 received in the aperture extends inwardly through said slot and is secured by brazing or otherwise to a radially projecting arm on a plate 46 whose contour will be clear from Fig. 5. The plate contains a central aperture 48 through which screw 30 extends, and a coiled compression spring 50 encircling the shank of the screw urges the plate upwardly toward the bottom of insulator 28.

Thus it will be seen that as ring 38 is turned relative to cap 22, pin 44 and plate 46 turn with it about the screw 30, such movement being limited, however, by the ends of slot 42 which serve as stops for the pin and hence for the other parts. When plate 46 is in the one of its limit positions which is illustrated in Figs. 4 and 5, its lip 46a engages terminal 34 and, under the influence of spring 50, makes firm electrical contact therewith so that it completes a circuit from the base of the lower battery 12 through spring 32, terminal 34, plate 46, spring 50, cap 22 and housing 10 to the lamp 20 in order to energize the lamp. When, upon rotation of the ring 38 counterclockwise (Fig. 5), plate 46 is turned to its other limit position, its lip 46a is disengaged from terminal 34, breaking the aforementioned circuit to turn the lamp off. A pair of circumferentially spaced dimples 52 in the plate are positioned to register with a ball 54 in the insulator in the two limit positions of the plate, and under the influence of spring 50, these assist in indexing the plate in the respective limit positions.

Returning now to the headpiece 14, it will be seen from Figs. 2 and 3 that this has a trough-shaped medial portion 56 of segmento-cylindrical contour, with a pair of upstanding laterally spaced ribs 58 and 60 on either side of the trough portion. Rib 60, which is thicker and extends relatively higher than rib 58, contains the socket 18 for lamp 20, it being understood that the socket runs longitudinally of this rib; thus, the axis of the lamp is offset laterally from the axis of the tubular housing or handle 10, and these two axes are crosswise of one another. In other words, the light from lamp 20 is projected in a direction generally normal to the axis of the handle.

The adjacent sides of the two ribs are undercut as shown at 62 to form marginal lips or flanges overhanging the edges of the segmento-cylindrical trough portion therebetween. This provides a channel-like guideway or supporting socket for receiving the arcuate shank portion 64 of the laryngoscope blade 66. When the shank is slid into this receiving recess or socket, it is retained in place by a spring-pressed ball or detent 68 which seats in a registering dimple 70 in the shank. Thus the blade cannot be displaced accidentally, but it can, of course, be withdrawn by pulling outwardly on the blade with sufficient force to depress the ball against the tension of its biasing spring 72.

In order that my laryngoscope can be used in connection with patients of all ages from premature infants to the very largest adults, a variety of blades ranging in size from small to large can be accommodated, it being understood that all

such blades must have shank portions identical to that shown so that they can be mounted interchangeably on the headpiece 14 of my unit. The blades may depart from the general shape illustrated where the facial bone construction of the patient or other special considerations dictate such change, but this shape can be used and is preferred in the majority of cases.

The preferred form of blade, it will be seen, has an elongate relatively broad and flat tongue-depressing portion which extends forwardly of the stem 64; one lateral edge of this portion is turned upwardly and back toward the center of the blade in a smoothly rounded roll to form an open channel which is aligned longitudinally with the lamp 20. In use, as shown in Fig. 1, the flat base portion holds down the patient's tongue 74 while the doubled-back lip 76 provides a rest or stop for the upper teeth 78. At the same time the channel between these two parts tends to contain the light from lamp 20 against general dispersion in all directions—in other words, it serves as a beam guide, concentrating and focusing the light to travel longitudinally of the blade so it projects beyond the end thereof in a relatively intense beam. By looking down the troughlike groove in the headpiece and along the blade, the laryngoscopist thus has a well-illuminated view of the throat and larynx.

The blade shown and the other blades which are interchangeable therewith are preferably made of stainless steel and can be produced economically in a variety of shapes and sizes. Since they do not themselves carry the lamp bulb or any electrical circuit elements, and since they may easily be withdrawn from the handle (which contains all of the electrical components of my unit), the blades can readily be sterilized by boiling, autoclaving or by simply drawing them through a flame. The ease with which one blade may be substituted for another on the handle will be obvious.

From the foregoing, it will be seen that this invention is one well adapted to attain all of the ends and objects hereinbefore set forth, together with other advantages which are obvious and which are inherent to the apparatus.

It will be understood that certain features and subcombinations are of utility and may be employed without reference to other features and subcombinations. This is contemplated by and is within the scope of the appended claims.

Inasmuch as various possible modifications of the invention may be made without departing from the scope thereof, it is to be understood that all matter herein set forth or shown in the accompanying drawings is to be interpreted as illustrative and not in a limiting sense.

Having thus described my invention, I claim:

1. In a laryngoscope, a tubular battery housing, a headpiece mounted on said housing at one end thereof, said headpiece having a pair of laterally spaced ribs disposed crosswise of the axis of the housing with a trough-shaped channel between the ribs terminating at its lateral edges in undercuts running longitudinally of the confronting inner surfaces of the ribs, an elongate blade having at one end a trough-shaped shank slidably received in said channel with its opposite longitudinal edges seated against said undercuts whereby said ribs are on either side of said shank, one of said ribs extending higher above the shank than the other and also being thicker than the other rib in transverse cross section, said one rib containing a socket extending longitudi-

nally inward from the end of the rib whereby said socket is offset laterally from said shank, said socket being spaced above the level of said shank, a lamp supported in said socket and adapted to be energized by the batteries in said housing thereby to project a beam of light longitudinally of the blade along one edge thereof, said edge of the blade being turned upwardly and inwardly toward the center of the blade to form a C-shaped channel along the edge, said last channel being substantially coaxial with said lamp and socket thereby to guide the light from the lamp longitudinally of the blade toward the free end thereof and prevent the beam from spreading laterally beyond said one edge.

2. In a laryngoscope, a tubular battery housing, a headpiece mounted on said housing at one end thereof, said headpiece having a pair of laterally spaced ribs disposed crosswise of the axis of the housing with a trough-shaped channel between the ribs terminating at its lateral edges in undercuts running longitudinally of the confronting inner surfaces of the ribs, an elongate blade having at one end a trough-shaped shank slidably received in said channel with its opposite longitudinal edges seated against said undercuts whereby said ribs are on either side of said shank, one of said ribs extending higher above the shank than the other and also being thicker than the other rib in transverse cross section, said one rib containing a socket extending longitudinally inward from the end of the rib whereby said socket is offset laterally from said shank, said socket being spaced above the level of said shank, a lamp supported in said socket and adapted to be energized by the batteries in said housing thereby to project a beam of light longitudinally of the blade along one edge thereof, and said blade having along said one edge a light-concentrating beam guide including an upstanding longitudinal flange positioned beside the beam to prevent same from spreading laterally beyond said one edge of the blade.

3. A laryngoscope as in claim 2 having latch means for releasably securing said shank in said channel, said latch means comprising a socket extending inwardly from the channel, a detent positioned in said socket, spring means in the socket urging said detent outwardly toward said shank, and a dimple in said shank for receiving the detent.
4. A laryngoscope as in claim 2 having a cup-shaped cap screw-threadedly attached to the end of the tubular battery housing opposite said headpiece, a circular insulator in said cap, means for securing said insulator to the cap in spaced relation to the base thereof, said means including 10 spacers between the insulator and the base of the cap and a central screw extending axially from the cap and having threaded connection with the insulator for drawing same toward the base of the cap, a switch plate in the cap between the base 15 thereof and said insulator pivoted on said screw, a spring encircling the screw between the plate and the base of the cap urging the plate against said insulator, a ring encircling said cap and rotatable thereon, means connecting said plate to said ring to turn therewith between two end positions, a coil spring mounted on said insulator to press 20 against the end battery in said housing, and said spring having a terminal extending through the insulator in a position to be engaged by a portion 25 of said plate in one of said positions.

ERNST TRIER MÖRCH.
